UNITED STATES PATENT OFFICE.

ROBERT B. BACH, OF NEW YORK, N. Y.

NEEDLE.

No. 877,476.

Specification of Letters Patent.

Patented Jan. 28, 1908.

Application filed April 16, 1904. Serial No. 203,412.

To all whom it may concern:

Be it known that I, ROBERT B. BACH, a citizen of the United States, and a resident of the city of New York, (borough of Brooklyn,) 5 in the county of Kings and State of New York, have invented a new and Improved Needle, of which the following is a full, clear, and exact description.

My invention relates to an improvement 10 in needles, which is capable of general use, but has particular advantages when applied to surgical needles.

In ordinary needles which are operated by hand, the thread passes through an eye and 15 is doubled over at the butt of the needle to form two strands, which together with the needle have a thickness greater than that of the needle alone. In surgery this is a great disadvantage, as the thread or gut used is 20 liable to tear the flesh when it is pulled through the opening made by the needle. In all kinds of sewing also, this extra thickness tends to tear or distend the fabric or other material sewed, so as to spoil the appearance and lessen the strength of the seam 25 or stitch.

It is the chief object of my invention to obviate these difficulties and to produce a needle which the thread will follow without 30 any enlargement of the opening made by the needle.

With these and other objects in view, my invention consists of the arrangements and combinations hereinafter described and set 35 forth in the appended claims.

Reference is to be had to the accompanying drawings forming a part of this specification, in which similar characters of reference 40 indicate corresponding parts in all the figures.

Figure 1 is a longitudinal sectional view of a needle on an enlarged scale, with a preferred form of my invention applied thereto; Fig. 2 is a sectional view on the line 2—2 of 45 Fig. 1, on a further enlarged scale; Fig. 3 is an end view of the thread-holding attachment for the needle, also on an enlarged scale; Fig. 4 is a side view of the thread-holding attachment; Fig. 5 is a central sectional view of the thread-holding attachment, slightly modified and on the scale of 50 Fig. 2; and Fig. 6 is an end view of the modification shown in Fig. 5.

In the particular embodiment of my invention represented in Figs. 1, 2, 3 and 4, a 55 is the needle proper, and it is provided with

a longitudinal cavity a' extending part way up from the butt and adapted to hold the end of a thread. At the rear end of this cavity is a tapered cavity a^2 , and beyond 60 this a screw-threaded portion a^3 . The thread-holding element is represented by the letter b , and it is provided with a central longitudinal passage b' for the passage of a thread c . It also has a projection b^2 which 65 is screw-threaded upon its exterior surface to engage with the screw-threaded portion a^3 of the cavity in the butt of the needle proper. There is also a conical extension b^3 upon the end of this projection, which is 70 adapted to fit in the conical portion of the cavity a^2 , as shown in Fig. 1. This projection b^2 , b^3 , is provided with one or more slits 75 b^4 . These slits may extend the whole length of the parts b^2 and b^3 or any portion thereof, 80 and while it is more convenient to form them by slitting diametrically across the parts in two directions, it will be obvious that these slits may be made in any desired manner without departing from the spirit of 85 my invention. The part b^3 is so constructed that when it is removed from the needle proper it will be slightly larger than the conical cavity a^2 . The natural resiliency of the material will thus operate, when the portion 90 b^2 is screwed into the needle proper at a^3 , to cause the several lobes of the part b^3 to be forced together and grip the thread c passing through the hole b' . The end of the thread is designed to be received in the cavity a' . 95 For the purpose of screwing the element b into the needle a , flattened or cut-away portions b^5 are provided on the butt of the element b .

In the form shown in Fig. 5, the interior 95 surface of the cavity b' is roughened at b^6 for the purpose of more securely holding the thread or gut in position. A slot b^7 is also provided in the butt of the element b for the purpose of permitting the thread to enter it 100 and so leave the extreme rear end of the needle free from the thread so as to permit a thimble or equivalent device to be pressed against the butt of the needle without having any tendency to cut or injure the thread. 105 In the ordinary construction of needles, it is difficult to apply a thimble to a needle in order to push it through a heavy fabric, without incurring the danger of cutting the thread thereby. Either one of these modifications shown in Fig. 5 may be employed 110 without the other, and both are intended to

be used in the construction shown in the other figures if desired.

It will be seen that my invention is capable of application to all kinds of needles, whether straight or curved, cylindrical or flat, or whatever the shape, and to needles to be used for any purpose whatever. The advantages will be obvious. Instead of having two strands of thread passing along the sides of the needle and enlarging the opening formed by the needle, a single thread will pass from the center of the butt of the needle, and will be smaller than the needle itself, so that a clean opening will be made and there will be no tendency to tear the fabric, flesh, or other material upon which the needle is employed. The thread will be securely gripped by the needle, and the needle can be pushed through heavy materials without danger of injuring the thread.

When using cotton, linen, or silk thread, it can be more securely held in the needle by passing its end outwardly from the hole a' so as to project between the end of the part b^3 and the end of the cavity a^2 . By this arrangement the finest threads may be secured in the needle.

While I have referred especially to surgical needles, it is to be understood that my invention possesses peculiar advantages when applied to sail-making needles, embroidery needles, and various other kinds, and I do not wish to be limited to any particular type

of needle. It will also be obvious that the drawings illustrate certain structures in which my invention may be embodied, and I do not wish the invention to be limited to the exact constructions shown, nor to the particular elements described, except as indicated in the appended claims.

Having thus described my invention, I claim as new and desire to secure by Letters Patent:

1. A needle, comprising a body portion having a cavity in its butt end, said cavity being threaded and having a conical portion, and a thread holding member having a longitudinal bore and a reduced and threaded portion, the threaded portion being slotted and terminating in the plain conical portion.

2. A needle comprising a body portion having a longitudinal cavity in its butt end, the outer portion of the cavity being screw-threaded and having a plain conical portion below the threaded portion, and a thread holding member having a longitudinal bore and a threaded and resilient inner end terminating in a conical portion.

In testimony whereof I have signed my name to this specification in the presence of two subscribing witnesses.

ROBERT B. BACH.
